CRUSHING MACHINE FOR ROCKS
AND THE LIKE

Einar H. Anderson, Minneapolis, Minn.

Application January 6, 1944, Serial No. 517,167

4 Claims. (Cl. 241—155)

1

This invention relates to machines for crushing hard materials, such as rock, and involves a number of improvements upon rock crusher structure disclosed in my Patent No. 2,383,457, the application for which was co-pending herewith.

Crushing units are often employed in complete crushing and screening plants to prepare crushed rock and aggregate for use in road surfacing. My invention relates to such units for crushing rock and other relatively hard materials whether used independently of or in conjunction with screening plants and other apparatus.

It is an object of my present invention to provide a compact high capacity rock crusher adapted to successively and continuously operate upon materials varying considerably in size and adapted to quite accurately divide or reduce such materials into a relatively wide range of sizes as desired.

A further object is the provision of a highly efficient rock crusher embodying in one machine two successive crushing steps utilizing reciprocating jaw and crushing roll principles respectively and so combined and related as to very efficiently utilize power available and to more uniformly and smoothly apply the crushing impulses than in machines heretofore utilized.

More specifically it is an object to provide a high capacity rock crusher, utilizing a stationary jaw in the primary crushing operation and utilizing a crushing roll for the secondary and finer reduction, in combination with one or more common jaw-carrying members reciprocated in opposition to both said stationary jaw and said crushing roll, and to further provide a materially greater area of crushing in the secondary reduction step with related control of material delivered therein, whereby the machine is given an exceedingly high capacity and sizing efficiency for the power utilized.

Another object is the provision of an improved rock crusher wherein a plurality of reciprocating jaw carrying members disposed in side by side relation are successively operated by a common source of power, preferably a common actuating shaft, to successively apply crushing pressure on relatively small areas of a common cooperating crushing member, such as a stationary jaw or roll, thereby producing a more steady stream of power impulses and crushing operations and materially

2

increasing the capacity, accuracy and durability of the machine.

Another object is the provision of a rock crushing machine of the type described wherein efficient adjustment mechanism is provided for varying the size of the reduced material within relatively wide limits and for also varying the output capacity of the machine.

A further and more specific object is the provision of an improved rock crusher of the type described having simple but highly efficient mechanism for adjusting the crushing stroke of the reciprocating jaw carrying member, or members, giving a greater range of adjustment with application of less power than has been accomplished by prior art machines.

Another object is to provide in a rock crusher utilizing a reciprocating jaw, or a plurality of reciprocating jaws, working in opposition to a crushing roll, a relationship between the opposed crushing surfaces with provision for limited adjustment of such relation by raising or lowering the concave surface of the reciprocating jaw to meet numerous requirements for producing reduced material of varying size as well as to speed up or slow down passage of material from my machine.

Still another object is the provision of efficient means for scraping gummy material from the reciprocating jaw during operation of the machine.

These and other objects and advantages of my invention will more fully appear from the following description made in connection with the accompanying drawings, wherein like reference characters refer to the same parts throughout the several views, and in which—

Figure 1 is a view partly in side elevation and mostly in vertical section of an embodiment of my invention, designed for high capacity operation;

Figure 2 is a vertical cross section taken on the line 2—2 of Figure 1 looking in the direction indicated by the arrows;

Figure 3 is a detail sectional view taken along the inclined line 3—3 of Figure 1 illustrating the mechanism for controlling the distribution of incoming smaller material upon the crushing roll;

Figure 4 is a detail sectional view taken along the inclined line 4—4 of Figure 1 looking in the direction of the arrows and showing my power

means for protrusively adjusting the pivot seat of the toggle plate to vary the clearance or jaw openings between the cooperating jaws;

Figure 5 is an elevation of the receiving end of my crushing machine;

Figures 6 to 8 are diagrammatic side elevational views showing the relationships of the concave surface of the common reciprocating jaw member to the opposed crushing roll in maximum retracted or material-receiving position, completion of crushing stroke and material discharging positions respectively;

Figure 9 is a similar diagrammatic view showing the relationship between the concave crushing surface of a reciprocating jaw and the concave surface of the crushing roll when adjustment has been made for crushing material to a finer mesh; and

Figure 10 is a similar diagrammatic view showing the relative positions of the concave crushing surface of the reciprocating jaw and its opposed portion of the crushing roll when adjustment has been made for producing a coarser processed material with the machine working at high capacity; and

Figure 11 is a vertical section illustrating the simplified embodiment of my invention.

In the drawings a crusher unit forming a part of a complete crushing and screening plant is illustrated, comprising a main frame H having illustrated, comprising a main frame H having heavy vertical side plates 10 which are suitably secured together and spaced apart and which have inwardly offset upper wall portions 10b defining the sides of an upper crushing chamber and further acting as a support for a heavy actuating shaft 11. A heavy tie 12 connects and reinforces the upper wall portions 10b at the material receiving end of the machine, having a jaw carrying surface inclined rearwardly slightly from the vertical and to which a stationary jaw plate 13 is detachably secured. The jaw plate 13, as shown, extends the entire distance between the two side plates 10b of the frame and may be provided with a multiplicity of flutings or ribs extending upwardly and downwardly of the jaw.

A rotary axle 14 is mounted transversely of the frame journaled in heavy bearings 15 secured to the outer surface of the lower side plates 10 and disposed some distance below the stationary jaw plate 13. Axle shaft 14 has affixed thereto a relatively large crushing roll 16 constructed of suitable hardened material. This crushing roll is disposed below the tie member 12 and the jaw carried thereby in spaced relation thereto to permit material to be fed to the top of the crushing roll from the rear of the machine in a line of travel substantially tangential to the roll 16. As shown, a declined delivery screen or chute 17 is supported to the rear of and above roll 16 with its inner or delivery edge disposed slightly forward of the vertical diameter of the roll 16.

I provide a plurality of reciprocating, jaw-carrying pitmans 18 cooperating with both the stationary jaw 13 and the crushing roll 16 to produce two stages or steps of crushing operations. For purposes of illustration a rock crusher having only two of said reciprocating pitmans is illustrated in the drawings, although it will be understood that a greater number may be utilized to better balance the crushing operations and to provide for a more steady stream of crushing impulses against the stationary jaw 13 and crushing roll 16. Each of the jaw carrying pitmans 18 is journaled upon an actuating eccentric 19 fixed to or otherwise provided upon the horizontal

actuating shaft 11, said shaft being journaled in heavy bearings attached to the upper and forward portions of the upper plates 10b of the frame. The two eccentrics 19 have their axes angularly spaced apart relatively to the axis of shaft 11 to cause successive crushing operations on the part of the respective pitmans 18.

The ends of actuating shaft 11 extend considerably beyond the side plates 10b of the frame and have attached thereto large fly wheels 20, one of which may be driven by belt or otherwise from a suitable source of power. A horizontal transverse counter-shaft 21 traverses the lower portion of the frame below the actuating shaft 11, extending through the widely spaced side plates 10 and as shown being journaled in suitable bearings 22 attached to the outer sides of side plates 10. The bearings 22 are eccentrically mounted in the heavy collars 22a which are adjustably affixed to side plates 20 to provide for oscillatory adjustment of said collars with eccentric effects for positioning bearings 22 for chain tightening purposes in the driving of the machine. Counter-shaft 21 is suitably driven from actuating shaft 11 and as shown a heavy roller chain 23 is trained about a driving sprocket 11a fixed to one end of shaft 11 and about a relatively large driven sprocket 21a fixed to the corresponding end of counter-shaft 21.

The opposite end of counter-shaft 21 as shown has affixed thereto a driving sprocket 21b for driving the crushing roll 16. The shaft 14 of the crushing roll is provided with a relatively large sprocket 14a affixed to the projecting end thereof on the same side of the frame as driving sprocket 21b and an endless roller chain 24 is trained about sprockets 21b and 14a for driving the crushing roll at relatively high rate of speed.

The heavy pitmans 18 are for the most part of the conventional construction used in rock crushers and have enlarged horizontal journals 18a at their upper ends which surround the respective eccentric cylinders 19 of the actuating shaft, suitable roller bearings and races being interposed between said parts for smoothly resisting wear. The pitmans 18 are provided along their rear edges and adjacent their lower ends as shown with adjustable, double fulcrum seats 25, each of said seats having two spaced seating channels 25a adapted for reception of the forward edge of a toggle plate 27 and each being interposed for limited vertical adjustment through the medium of one or more spacers or shims 26 between heavy seat attachment lugs 28, rigidly secured to the pitmans. Each of the toggle plates 27 is of conventional structure, having a weakened central portion 27a extending throughout the length thereof and having its rear edge seated in an elongated pivot seat or groove 29 which is adjustably mounted in a tie frame 30 connected across the side plates 10 of the frame at the lower forward corner thereof. The construction of this seat and its adjustment mechanism is of special and improved construction and will be described later in detail. The lower end of each of the pitmans 18 is connected by a spring tensioning link designated in its entirety by the numeral 31 with the transverse tie plate or frame 30, said spring link holding the fulcrum seats of the pitmans at all times against the forward edge of the toggle plate.

Each of the pitmans 18 has detachably secured to its inner longitudinal face a pair of jaw members 33 and 34 opposed respectively to the upper stationary jaw 13, and to one side of the crush-

ing roll 16. The upper jaws 33 of the two pitmans are of approximately one-half the width of stationary jaw 13 and are opposed thereto in side by side relationship as clearly shown in Figure 2 and may be provided with longitudinal flutings or ribs to match the flutings of the stationary jaw 13. By reference to Figures 2 and 5 it will be noted that the upper crushing chamber defined between the upper plates 10b of the frame is substantially of less width than the lower crushing chamber extending between the lower main plates 10 of the frame and that the ends of crushing roll 16 project outwardly for considerable distances beyond the outer longitudinal edges of the upper reciprocating jaws 33. The lower reciprocating jaws 34 are thus formed to each oppose approximately half of the length of crushing roll 16 and are removably secured to the lower portion of the respective pitmans faces and as shown have concave crushing surfaces 34a arcuately curved on substantially the radius of crushing roll 16, and are positioned and related to the opposed peripheral surface of the crushing roll, at the maximum crushing positions of pitmans 18, in substantially concentric relation therewith for customary operation of the machine. The upper crushing area of the lower jaws 34 may be more or less planar as shown, or may be concave as illustrated in my herein identified co-pending application, but in any event diverges angularly from the lower concave crushing surface 34a and also from the opposing portion of the crushing roll, defining with the lower concave surface 34a a ridge 34b which has an important classifying function in the operation of the machine and particularly in controlling and directing the material received for crushing between the lower concave portion of the jaw 34 and the crushing roll as will herein be more fully explained.

It is desirable for certain purposes of adjustment in varying the speed and capacity of the machine for production of particles of varying size, that the relationship of the concave crushing surface 34a and the opposed portion of the crushing roll be vertically varied within a slight range. While this variance in the said relationship may be accomplished in several ways, as shown in the drawings, I provide above and below the respective horizontal jaw edges of member 34, a series of spacing elements or shims 35 which may be removed or re-arranged to position jaw member 34 somewhat higher or somewhat lower, as desired to its position shown in the drawing. The jaws 33 and 34 may be removably secured to the respective pitmans 18 in any suitable manner and as shown, rectangular retaining clips 36 are employed for engaging certain of the transverse edges of the jaws, clamped to the pitmans by suitable clamping bolts 36a.

The upper longitudinal edges of the upper jaws 33 are secured by undercut longitudinal receiving edges 18b formed just below the journals 18a at the upper portions of the pitmans. The lower edges of the lower jaws 34 as shown, are clamped by upwardly extending clamping bolts 37 threadedly engaging the flanged jaw-holding edges 18c at the lower edge of pitmans 18.

In Figures 2 and 3 I illustrate suitable mechanism for controlling distribution of less coarse material to the top of crushing roll 16, said mechanism as shown comprising a pair of diverging adjustable deflector plates 39 pivoted at their outer ends to a common hinge axis 40 which extends normal to the screen chute 17 and having their lower edges disposed flush against the top

of said screen. The hinge for deflecting plates 39 is secured to and supported from a rearwardly extending post 41 which as shown is rigidly attached to a mounting plate or bracket 42 secured as by bolts 43 to the rear edges of the longitudinal ribs 12a, provided by the heavy tie member 12 which carries stationary jaw 13. The deflector plates 39 are angularly adjustable through wide limits by means of pivoted links 39a pivoted to the inner sides thereof and each having at the outer end thereof a series of attachment apertures adapted to receive an upstanding pin 41a provided by the supporting post 41. It will be seen that the less coarse material delivered to the machine by the screen chute 17 which is provided with guiding sides 17a, may be deflected as desired, to be distributed through substantially the entire top of crushing roll 16 or may be deflected for distribution throughout various areas adjacent the ends of roll 16.

I provide scraper means associated with the revolving crusher roll to prevent accumulation of gummy material upon the concave crushing surface 34a of the lower jaw. As shown, this mechanism comprises a scraper blade 44 of channel construction mounted longitudinally upon the periphery of roll 16 with its channel disposed outwardly and as shown removably secured to the outer roll by a plurality of clamping bolts 44a. The edges of the channel bar are adapted to scrape against the concave surfaces 34a of the lower jaw during the operation of the machine, removing any gummy or sticky material therefrom in the innermost positions of the reciprocating jaws.

To protrusively adjust the toggle pivot-seat 29, and consequently the clearance of the reciprocating jaw, efficient mechanism is provided as shown in Figures 4 and 1.

The heavy tie bar or frame member 30 which connects the lower portions of the side walls 10, rigidly carries a pair of spaced perpendicular inwardly extending webs 30a between which the adjustment elements for the pivot seat are slidably mounted. The back web or upstanding body portion 30 of the tie member constitutes a seat or bed for the adjustment mechanism and inwardly of said bed a plurality of removable spacer bars 45 are disposed. Opposed rectangular apertures 10c are formed in the vertical frame walls 10 aligned with the space between the housing webs 30a to facilitate removal of one or more of the spacing bars 45 from one or both sides of the machine. The pivot seat member or block 29 has oppositely inclined or beveled surfaces 29a at its rear side extending longitudinally of the block from the center thereof to the end, the inclination of said beveled surfaces being of relatively small angularity, preferably less than 30°. I provide a double wedge mechanism interposed between said beveled surfaces 29a and the base of resistance of the adjustment mechanism, which as shown comprises a pair of aligned wedge blocks 46 having plane surfaces extending perpendicularly to the ends thereof for engagement with the inner surfaces of the innermost spacer bar 45 or the tie bar 30 as the case may be and having inclined or beveled surfaces 46a complementarily formed and angled for engagement with the oppositely beveled thrust surfaces 29a of the pivot seat block 29. Each of the wedge blocks 46, as shown, is provided with a tapped core 46b constructed of suitable hard metal, the cores 46b of the two wedge blocks being oppositely threaded to engage the opposite threads of a double screw-operating member 47 which is dis-

posed transversely of the machine and has, as shown, squared manipulating ends 47a extending beyond the walls of the machine frame for connection with an adjustment crank or other device for turning the double screw.

With my said toggle pivot-seat adjustment mechanism, because of the combination of the removable spacer bars 45 with the wedge mechanism having wedge surfaces angled quite gradually, power application is multiplied when the double screw 47 is turned and wide adjustability of the pivot seat and consequently the spaced relationship of the crusher jaws is efficiently obtained. Thus when it is desired to space the crusher jaws widely apart, one or more of the spacer bars 45 may be removed through one of the lateral apertures 10c in the frame wall and the wedge mechanism adjusted properly thereafter.

To close the apertures 10b in the frame walls 10, to prevent leakage of oil or lubricant and access of foreign material to the adjustment mechanism, I provide at each side of the machine frame a closure plate 48 which overlaps the associated aperture 10b. Each of the closure plates 48 is provided for bolt and slot connection with the edges defining the aperture and secured adjustably over the aperture by bolts 48a. The plate is sufficiently long in each instance to cover the aperture and provide a bearing 48b for the double screw member in the various positions of the wedge blocks 46 when one or more of the spacer bars 45 are removed.

Operation

The crushing unit illustrated in Figures 1 to 10 inclusive and herein previously described, is associated with a crushing and screening plant having a feed conveyor (not shown) and having a classifying two-deck screen of which fragments of the upper coarser screen 50 and the lower finer screen 17 are shown in Figure 1. In such a plant the coarse material to be ground is conveyed by the screen chute 50 to the top crushing jaws and the material crushed is received below the machine by return conveyor not shown and conveyed to the finer screen 17 for secondary grading, the finely ground material dropping through screen 17 into a collection bin shown in Figure 1.

It will, of course, be understood that my crushing machine, or unit, including the efficient crushing cooperation between revolving roll 16 and the reciprocating jaws 33 and 34 per se, may be utilized in many installations and for many purposes all within the scope of my invention.

In operation rocks or other hard material of 12-inch ring size or smaller are delivered to the top screen chute 50 which separates off the larger material to be crushed above a predetermined size—say for example, a size in excess of 2 inch ring. The small rocks and material drop upon screen chute 17 and are fed thereby between the heavy tie bar 12 carrying the fixed jaw 13 and the roll 16 being delivered to the top of the roll which guides the smaller material between the crushing portion of the roll and the reciprocating jaw 34. The fines, of course, drop through screen 17 and are collected in the bin or hopper B. The larger rocks and material are fed by the coarse screen chute 50 and the top of jaw 13 to the entrance of the machine between stationary jaw 13 and the upper reciprocating jaws 33 where they are crushed and reduced to smaller size. In the successive reciprocation of the two or more pitmans 18 the jaws 33 and 34 are moved success-

ively toward the stationary jaw 13 with a compound downward movement as they approach maximum crushing position, this downward movement tending to draw the material downwardly between the jaws. The distribution of applied power with my improved device is greatly improved over machines of the prior art since a plurality of pitmans are used having eccentric connections with the main shaft 11 at varying angles to successively move the several jaws against the associated crushing elements, thereby improving the crushing efficiency of the machine and more uniformly applying crushing power against the upper stationary jaw and the crushing roll.

The material crushed between stationary jaw 13 and the upper jaws 33 of the pitmans drops by gravity to the secondary crushing mechanism below and is fed between the roll 16 and the lower jaws 34 of the pitmans. To this material is added material which is being fed to the machine by the declined classification screen 17 entering the machine laterally between the stationary jaw 13 and the top of crushing roll 16. By reference to Figures 6 to 8 it will be seen that in view of the compound movement of the pitmans and the cooperation between the roll 16 and my lower jaws 34 particularly the concave portion 34a, the receiving position between the lower jaws of the crushing roll as shown in Figure 6 presents a converging space for the material dropping by gravity from the first crushing operation or fed into the machine by screen 17 and thereafter in the maximum crushing stroke or position shown in Figure 7 causes disposition of the concave surfaces 34a of the lower jaws in substantially concentric relation with the crushing roll and thereafter as pitmans 18 are retracted from the crushing roll, presents a diverging space between the cooperating portion of the roll and the concave portions 34a of the jaw for discharge of crushed material by gravity and with the assistance of the revolving roll. At the times of discharge and of maximum crushing (Figures 8 and 7 respectively) it will be noted that the transverse rib 34b defined by the intersection of the concave jaw portion 34a with the upper substantially flat contiguous jaw portion, is maintained at more or less a predetermined spaced relation to the contiguous surface of the crushing roll acting as a classifying mechanism to prevent reception and discharge of material below a predetermined size as the jaw is retracted from the crushing roll. The surface above the concave surface 34a of the lower jaws is angled with respect to the concave surfaces and with respect to the crushing roll and diverges sharply from the crusher roll to properly guide the material for the secondary crushing.

Thus an efficient control of the feeding of all material between the crushing and cooperating lower jaws 34 is provided with the withholding of this first crushed material between the crushing roll 16 and concave portion of the lower reciprocating jaw 34 until one or more full strokes of the reciprocating crushing jaws have acted upon the material. The material crushed between the roll and lower jaws drops in the discharge strokes of the respective lower jaws upon a return conveyor (not shown), if desired, which delivers to an elevator (not shown) which delivers to a feeding conveyor (not shown) carrying this material to the classifying screens or at least to classifying screens 17, the fines then passing through screens 17 into the collection bin B.

In the crushing of the material between the roll 16 and reciprocating jaws 34a the jaws move

at relatively high speed to the travel of the roll. The speed ratio, timing and relationship of the concave areas with the resultant slight tilting of the pitmans in their reciprocation with the small downward and upward component movements are such that preferably material will not be released at the bottom of the machine until it has been subjected to at least two crushing strokes of the reciprocating jaw. The control effected by the relationship of the ribs 34b at the upper edge of the concave crushing surfaces is important in cooperating to this unitary result and consequently the crushed material dropping from the bottom of the machine is of quite uniform size. This means that a much smaller percentage of material must be returned to the machine for a second crushing than in crushers now extensively utilized.

Great latitude for adjustment in the spaced relation and positioning of the lower jaws 34 and particularly the concaved portions 34a to the associated side of the crushing roll is made possible with my improved construction. The spaced relation may be readily adjusted by the double screw actuated mechanism for adjusting the pivot seat 29 of the toggle. Adjustment of the fulcruming of the pitmans 18 within limits is made possible with my improved structure, first by selectively engaging the inner or upper edge of the toggle plates 27 with one of the other of the recesses 25a of the fulcrum seats 25 secured to the respective pitmans and secondarily by re-arranging the shims, or shims, or other spacing means 26 interposed between the seat block 25 and its attachment lugs 28.

Another very important relational adjustment which is obtained with my improved apparatus is effected through the provision of means for vertically adjusting the concave surfaces 34a of the lower jaws relative to the cooperating side portions of roll 16. The provision for such adjustment in the embodiment shown comprises a plurality of spacer strips or shims 35 interposed between the upper and lower edges of jaw 34 and its seat and securing members, whereby the rearrangement of the shims, as illustrated in Figures 9 and 10 and the relation of the concave surfaces 34a of the jaws to the crushing roll can be changed within limits.

In Figures 9 and 10 the lower jaws and rolls are illustrated in extreme crushing position. In Figure 9, the lower jaw has been raised above the position shown in Figures 1 and 6 to 8 of the drawings. This is desirable where a very fine grade of the output of material is desired and where the material fed into the machine is not too coarse. In the adjusted position shown in Figure 9, which it is to be remembered is the maximum crushing position, the concave surface 34a is not disposed quite concentrically of roll 16 but diverges from its upper to its lower portion, the rib 34b still acting as a classifying medium but the lower ribs 34c defined by the intersection of the concave surface with the lowermost surface of the jaw also being a classifying medium and serving to retain material for one or more additional crushing strokes before it is discharged from the machine.

In Figure 10 the positional relationship of the lower crushing jaw 34 has been reversed from that shown in Figure 9, Figure 10 being in lowered position obtained by shifting of spacing shims 35, than the usual operating position shown in Figure 1 and Figures 6 to 8. Again it is to be remembered that in Figure 10 jaw 34 is shown in

its maximum crushing position relative to the roll 16. Here it will be seen that the space between the jaw and roll diverges from top to bottom of the crushing area, thereby tending to speed up discharge of material and the rib 34b of the upper edge of the concave surface chiefly acts as the classifying medium. This positional relationship shown in Figure 10 is preferred for the crushing of coarser products and for speeding up the capacity of the machine, and the material crushed between roll 16 and jaws 34 may be subjected to only one complete crushing action before discharge.

The area relationship between the upper reciprocating jaws 33 and the lower jaw 34 which crush against the roll as well as the distribution of the crushing load is very important. With my construction the feed gates or deflector plates 39 mounted edgewise upon the screen chute 17 may be adjusted depending upon the amount of material at any predetermined time which is fed to the secondary crushing mechanism by screen 17 to obtain a substantial uniform crushing load over the entire length of crushing roll 16. Thus if the raw material to be crushed contains a considerable percentage of small material which passes through the upper classifying screen 50, the gates are adjusted to distribute pretty uniformly to the greater portion of the crushing roll. While if only a relatively small amount of smaller sized material is being fed into the machine over the screen chute 17, the gates are adjusted to direct most of this material to the outer or end portions of the crushing roll since the load upon the central portion of the crushing roll will be relatively heavy due to a greater percentage of raw material being crushed by jaws 33 and the stationary jaw.

From the foregoing description it will be seen that I have provided a comparatively light, high-powered crushing unit having a very high efficiency and capacity for its weight and for the power applied and particularly adapted for a number of different adjustments to suit particular requirements as to size of the crushed material desired.

In Figure 11 a simplified crushing machine is illustrated employing many of the features of the form of my invention first described. In this machine no stationary crushing jaw is utilized but all crushing operations are effected between a reciprocating jaw 51 and a revolving crusher roll 52. The mounting, toggle mechanism and adjustment mechanism for the pitmans and reciprocating jaw 51 are similar to the machine first described and, therefore, need not be here described in detail. The jaw 51 has an upper concave crushing portion 51a which diverges considerably from the lower portion thereof to its upper portion with reference to the cooperating side of crushing roll 52 and is preferably provided with a series of transverse teeth or ribs 51b to cause the larger material introduced to be gripped and prevented from upward slipping.

This upper concave crushing surface 51a merges at its lower edge with a lower concave crushing surface 51c defining in its intersection with said lower concave surface a classifying rib 51d, the said upper surface diverging materially from the curve or segment of the lower concave surface 51c. The lower concave surface 51c is preferably unribbed and uncorrugated.

While the jaw 51 may be integrally formed throughout to define the two concave crushing portions or surfaces 51a and 51c, I prefer to form

a concave crushing jaw portion 51c through the provision of a replaceable jaw section. Thus this jaw section 51c which receives more wear than the upper concave section 51a may be readily replaced and, as shown, is attached to the pitmans by means of a plurality of clamping bolts 54, which extend through truncated conical apertures disposed in transversely spaced relation across the pitmans.

In this form of my invention the crushing roll is revolved in clockwise direction to assist in feeding material between the cooperating crushing members and to move such material downwardly for crushing and discharge, and the fast reciprocating jaw will first crush the coarser material between the upper concave area and the crushing roll, such material after original crushing, working down and being classified by the relation of the lower concave crushing surface 51c and classifying rib 51d into position between the lower concave crushing surface 51c and the lower side of the crushing roll 52 opposed thereto. Secondary crushing then takes place and the material in sub-divided state and in fairly uniform size is delivered at the bottom of the machine.

Here again as illustrated in Figures 9 and 10 the positional relationship of the lower concave crushing surface 51c may be varied within limits through the arrangement of two sets of spacing strips or shims 35 between the edges of the jaw member 51 proper and its seated edges. In this form of the invention two or more reciprocating jaws may be employed in opposition to the revolving roll, if desired, to more uniformly and efficiently distribute the power from its source and the application of that power against the crushing roll.

It will, of course, be understood that various changes may be made in the form, details, arrangement and proportions of the parts without departing from the scope of my invention.

What I claim is:

1. In a crushing machine, a rotary crushing roll, a reciprocating crushing jaw opposed to one side of said roll, means for revolving said roll in a direction to cooperate with said reciprocating jaw for material feeding and crushing purposes, means for reciprocating said jaw toward and away from said crushing roll with a compound, limited downward movement as said jaw approaches said roll, said jaw having a lower concave crushing surface opposed to a side of said roll and extending substantially concentric thereof and said roll carrying a longitudinally extending blade protruding from the periphery thereof for engaging said jaw to scrape sticky material therefrom.

2. In a crushing machine, a stationary crushing jaw inclined somewhat from the vertical position, a horizontal crushing roll mounted below said stationary jaw and spaced therefrom, said roll being substantially longer than the width of said stationary jaw with its ends projected beyond the sides of said jaw and mounted with one side of its periphery disposed at least close to vertical alignment with the lower edge of said stationary jaw, a plurality of common reciprocating jaw-carrying members opposed to both said stationary jaw and said crushing roll, a plurality of upper crushing jaws attached to said reciprocating members and disposed in side by side relationship and having an aggregate width substantially equal to the width of said stationary jaw, a plurality of lower crushing jaws also secured to said respective reciprocating member and disposed in side by side relationship in opposition to one side

of said crushing roll, the aggregate width of said lower jaws being substantially greater than the aggregate width of said upper jaws and being substantially equal to the length of said crushing roll, means for feeding coarse material between the upper portions of said stationary jaw and said upper reciprocating jaws, means for feeding less coarse material from outside of said machine over the projecting ends of said roll, means for revolving said roll to convey said last mentioned material downwardly toward said lower reciprocating jaws, means for reciprocating said plurality of reciprocating members in staggered relation to produce successive crushing operations of said several reciprocating jaws against said stationary jaw and said crushing roll, and means for varying the area of distribution of said less coarse material upon the top of said crushing roll.

3. In a crushing machine, a horizontal crushing roll, a reciprocating jaw-carrying member opposed to one side of said roll, means for revolving said roll in a direction to cooperate with said reciprocating member for feeding and crushing of material, means for reciprocating said member toward and away from said crushing roll with a compound limited downward movement as said member approaches said roll, a jaw attached to said reciprocable member and having a concave crushing surface opposed to one side of said roll and curved in general along a segmental path substantially concentric with said roll and means for supporting said jaw from and attaching said jaw to said reciprocable member in a plurality of different vertical positions relative to the lower end of said reciprocable member to thereby vertically vary the positional relationship of said concave crushing surface relative to the opposed cylindrical surface of said roll whereby the discharge of crushed material from the machine may be selectively retarded or expedited within limits.

4. In a crushing machine, a stationary crushing jaw inclined somewhat from the vertical position, a horizontal crushing roll mounted below said stationary jaw and spaced therefrom, said roll being substantially longer than the width of said stationary jaw with its ends projected beyond the sides of said jaw and mounted with one side of its periphery disposed at least close to vertical alignment with the lower edge of said stationary jaw, a plurality of common reciprocating jaw-carrying members opposed to both said stationary jaw and said crushing roll, a plurality of upper crushing jaws attached to said reciprocating members and disposed in side by side relationship and having an aggregate width substantially equal to the width of said stationary jaw, a plurality of lower crushing jaws also secured to said respective reciprocating member and disposed in side by side relationship in opposition to one side of said crushing roll, the aggregate width of said lower jaws being substantially greater than the aggregate width of said upper jaws and being substantially equal to the length of said crushing roll, means for feeding coarse material between the upper portions of said stationary jaw and said upper reciprocating jaws, means for feeding less coarse material from outside of said machine over the projecting ends of said roll, means for revolving said roll to convey said last mentioned material downwardly toward said lower reciprocating jaws, means for reciprocating said plurality of reciprocating members in staggered relation to produce successive crushing operations of said several reciprocating jaws against said stationary

13

Jaw and said crushing roll and means for controlling the feed of less coarse material from outside of said machine over said roll.

EINAR H. ANDERSON.
